UNITED STATES PATENT OFFICE.

ROBERT E. JACKSON, OF VICTORIA, AND FRANK E. BELL, OF NORFOLK, VIRGINIA.

SPARK-ARRESTER.

1,093,054.

Specification of Letters Patent. Patented Apr. 14, 1914.

Application filed April 17, 1913. Serial No. 761,796.

To all whom it may concern:

Be it known that we, ROBERT E. JACKSON and FRANK E. BELL, citizens of the United States, residing at Victoria, in the county 5 of Lunenburg, and Norfolk, in the county of Norfolk, respectively, both in the State of Virginia, have invented new and useful Improvements in Spark-Arresters, of which the following is a specification.

10 Our present invention pertains to spark-arresting means; and it contemplates the provision of a spark arrester designed more particularly, though not necessarily, for use in combination with a locomotive boiler, and 15 constructed with a view to precluding the escape of sparks through the uptake without interfering with the free passage from the boiler of smoke and heated gases, as is necessary to properly promote combustion in the 20 fire-box, and also constructed with a view to repassing a certain proportion of the heated gases and other products of combustion through the fire-box, this latter being materially advantageous inasmuch as it affords 25 a circulation of hot air and gases through the boiler flues when the engine is drifting, and in that way effectually prevents cooling and contraction of the flues and the objections attendant thereon.

30 Other advantageous characteristics of our invention will be fully understood from the following description and claim, when the same are read in connection with the accompanying drawings, hereby made a part hereof, in which:

Figure 1 is a side elevation of a locomotive boiler equipped with our novel spark-arresting means. Fig. 2 is a longitudinal vertical section, with some parts in elevation, 40 taken through the smoke-box of the boiler and illustrating the parts of our novel means located in the smoke-box. Fig. 3 is a transverse section taken through the smoke-box in a vertical plane in front of the foremost 45 wall of the diaphragm, looking rearwardly.

Similar numerals of reference designate corresponding parts in all of the views of the drawings.

In the preferred embodiment of our invention, the locomotive boiler is provided with conventional flues 1, and also with a conventional smoke-box 2 from which rises the usual uptake 3. We also employ, by preference, the ordinary well known exhaust pipe 4, arranged in vertical alinement with the uptake 3, and also arranged in communica-

tion with the exhaust cavities in the saddles 5 of the piston cylinders comprised in the locomotive. Also communicating with the said exhaust cavities in the saddles 5 are conduits 6, which lead to and communicate with an upstanding pipe 7 disposed in the longitudinal center of the smoke-box, and adjacent the forward wall 8 thereof.

As will be observed by reference to Fig. 2, the smoke-box is divided through the medium of a diaphragm into a compartment 9 that is in full and free communication with the flues 1, and a compartment 10 that is separated from the said flues by the said diaphragm. The diaphragm referred to is preferably sectional in character, and is made up of a transverse wall 11 shaped in outline as shown in Fig. 3, a downwardly and rearwardly inclined wall 12, a wall 13 through which the exhaust pipe 4 extends, a downwardly and forwardly inclined wall 14 interposed between and connected to the boiler shell and the wall 13, a wall 14^a extending downwardly and forwardly from the forward portion of the wall 13, and a foraminous plate 15 extending between and connected to the lower portions of the walls 12 and 14^a and inclined slightly downward and rearward, this in order to lessen the liability of sot or other substance clogging the apertures in the plate.

Communicating with and extending upwardly from the space between the walls 11 and 12 is the upstanding portion of a conduit 16, which upstanding portion receives the upper portion of the upright steam conduit 7, as clearly shown in Fig. 2. The said upstanding portion of the conduit 16 merges into a rearwardly and upwardly extending portion, and the latter, in turn, is connected in suitable manner with conduits 17 which have for their function to repass sparks heated air and gases through the fire-box of the boiler in order to prevent cooling and consequent contraction of the flues 1, as when the locomotive is drifted. As will be observed by comparison of the several figures of the drawings, the conduits 17 are carried laterally from the conduit 16, through the boiler shell, and exteriorly of said shell the said conduits are carried rearwardly at opposite sides of the boiler 18, and fire-box 19 to points in rear of the rear wall of the fire-box from whence they are extended through said rear wall at points 20 slightly above the bed of fire in the box, this

in order that the heated air and gases supplied through the conduits 17 will contribute toward preventing cooling of the grate, and at the same time the said heated air and gases 5 will be ignited before again taking passage through the flues 1. The said returned air and gases will also promote combustion in the fire-box, as is obvious, and this latter is true when the locomotive is drifting and also 10 when the locomotive is propelled by its own power and exhaust steam is supplied to the pipe 4 and the conduit 7.

In the practical use of our novel arrester, it will be manifest that the exhaust steam 15 discharged through the comparatively large pipe 4 will create a vacuum or partial vacuum in the chamber 10 at the opposite side of the diaphragm, with reference to the flues 1, and in consequence smoke, gases and 20 heated air will be forcibly drawn through the foraminous plate 15 and combustion will be adequately supported in the fire-box of the boiler. While smoke and other gaseous products of combustion will freely pass 25 through the apertures of the plate 15, the passage through said plate of sparks will be effectually prevented. This latter is due in part to the foraminous plate 15, and in part to the vacuum or partial vacuum created in 30 the conduit 16 by the discharge therein of exhaust steam from the conduit 7, since, as will be readily understood, a portion of the smoke and heated air and gases will be forced through the conduit 16 and the conduits 17, and during their passage to the 35 conduit 16 will tend to carry cinders past the plate 15 with the result that the cinders will be deposited on the bottom of the compartment 9 of the fire-box.

40 We have entered into a detailed description of the construction and relative arrangement of the parts embraced in the present and preferred embodiment of our

invention, in order to impart a full, clear and exact understanding of the same. We 45 do not desire, however, to be understood as confining ourselves to the said specific construction and relative arrangement of parts, as, in the future practice of the invention, we reserve the right to make such changes 50 or modifications as do not involve departure from the scope of our invention as defined in the claim appended.

Having described our invention, what we 55 claim and desire to secure by Letters-Pat-ent, is:

The combination in a locomotive, of a fire box, a smoke box, flues extending between and connecting the fire box and the smoke box, a diaphragm dividing the smoke box 60 into a rear chamber in communication with the flues, and a forward chamber; said dia- phragm including in its forward portion a foraminous plate, a smoke discharge leading from the upper portion of the forward cham- ber, a steam discharge pipe adapted to be connected with a source of steam supply and aligned with said smoke discharge and com- municating with the forward chamber, a 65 conduit leading from the forward portion of the rear chamber, at a point in front of the foraminous plate of the diaphragm, and back to and communicating with the fire box, and a conduit connected with a source of steam supply and arranged to discharge 70 steam into the said conduit that leads back to the fire box.

In testimony whereof we have hereunto set our hands in presence of two subscribing witnesses.

ROBERT E. JACKSON.
FRANK E. BELL.
